UNITED STATES PATENT OFFICE.

ANTHONY SCHUCH, OF DALLAS, TEXAS.

STOVEPIPE-FASTENER.

1,289,556.

Specification of Letters Patent. Patented Dec. 31, 1918.

Application filed January 9, 1918. Serial No. 211,067.

To all whom it may concern:

Be it known that I, ANTHONY SCHUCH, a citizen of the United States, residing at Dallas, in the county of Dallas and State of 5 Texas, have invented certain new and useful Improvements in Stovepipe-Fasteners, of which the following is a specification.

This invention relates to new and useful improvements in stove pipe fasteners.

10 It is customary in building flues to place sheet metal thimbles in the chimneys for receiving the stove pipe. It frequently happens that the stove pipe is pulled out into the room which is not only dangerous but 15 generally results in the deposit of soil and soot on the walls and floor. I propose to provide means for fastening the stove pipe in the thimble and eliminate this trouble.

In carrying out the invention a member 20 is provided and secured in the thimble so as to receive the end of the stove pipe. Means is provided for fastening the stove pipe in conjunction with the said member whereby it cannot be removed from the 25 thimble until the fastening is disengaged. It is proposed to arrange the parts so that they may be concealed by the usual ornamental collar surrounding the pipe at the thimble.

30 In a more specific embodiment of the invention an elongated adjustable clamping member is provided and fastened in the thimble. The member is provided with a stop for receiving the end of the stove pipe 35 and limiting the distance to which it may be inserted in the thimble. A fastening device is mounted on the member and engages the stove pipe so as to lock it in the thimble.

This invention will be more readily understood from a reading of the following specification and by reference to the accompanying drawings, in which an example of the invention is illustrated, and wherein

45 Figure 1 is a sectional view of a thimble and component parts showing a stove pipe fastened therein in accordance with this invention,

Fig. 2 is a perspective view of the fastening device,

50 Fig. 3 is a side elevation, and

Fig. 4 is a detail of a slight modification.

In the drawings the numeral 1 designates a chimney to the flue and 3 is the sheet metal thimble which projects slightly into 55 the flue, but has its front end flush with

the face of the chimney. For fastening the stove pipe I provide an elongated member comprising a base portion 4 with an integral shank 5 extending from its rear end and a depending clamping lug 6 bent downward at right angles from its front end, said lug having spurs 7 on its inner face. The rear end of the shank 5 is provided with a transverse slot 8 and an offset end 9 having an upstanding stud 10. An elongated extension hook 11 is slidable through the slot 8 and is provided with a plurality of closely spaced transverse slots 12 located to receive the stud 10. At its outer or rear end the hook has a lip 13 adapted to engage over the inner or rear end of the thimble 3. Due to the offset 9 the hook is movable in a plane parallel to the parts 4 and 5 and thereunder. A loop 14 embraces the parts 5 and 11 and holds them in contact. When 75 it is desired to extend or retract the hook 11 the loop 14 is slid to the offset portion 9 as shown in dotted lines in Fig. 3 and at which position it co-acts with the slot 8 in permitting the hook to be swung upward and disengaged from the stud 10 whereby it may be adjusted. After the hook has been adjusted it is swung down so that the stud 10 enters 80 one of its slots 12 after which the loop is displaced to fasten the parts in position. 85

The device is placed in the thimble so that the lip 13 engages over the rear end of the thimble and the lug 6 depends over the face of the chimney. The lug is fastened by driving the spurs into the said face by 90 means of a hammer or other tool. On the base 4 a plate 15 is fastened at one end by ears 15' passed up through the plate and bent down upon the same, the front portion of the plate being free. A stop 16 is struck 95 up from the plate as shown. A wedge shaped lever 17 is pivoted to the base just under one of the front corners of the plate and has the depending finger grip 18. A boss 19 is struck up from the plate near its 100 front end.

As shown in Fig. 1 the stove pipe A is inserted in the thimble until its rear edge engages under and is arrested by the stop 16. Before the stove pipe is inserted it is 105 provided with a small opening B positioned to receive the boss 19. At the time the pipe is inserted the lever 17 is withdrawn and swung to one side as shown in dotted lines in Fig. 2. This permits the plate to lie 110

flat on the base whereby the stove pipe may pass over the boss 19. After the pipe is in position the lever 17 is swung inward whereby the plate 15 is displaced upward which 5 causes the boss to enter the opening B. It will be seen that the pipe A is thus locked in the thimble and cannot be moved either inward or outward. The usual ornamental collar C is placed on the pipe A and completely conceals the exposed parts of the 10 device. In Fig. 4 the hook 11 has a down-turned lug 20 instead of the lip 13 for use in chimneys where the thimble does not project into the flue. The lug 20 carries spurs 15 21 which bite into the wall of the flue.

When it is desired to remove the stove pipe the lever 17 is withdrawn by means of the grip 18 and then by inserting a screw-driver or other flat tool between the plate 15 20 and the stove pipe said plate may be sprung down to withdraw the boss from the opening B and with the parts held in this position the pipe may be withdrawn.

The foregoing description and illustration clearly express the invention, but it is 25 to be understood that said illustration is

merely an exemplification and the invention may be carried out in various other ways.

What I claim, is;

1. In a stove pipe fastening device, a base 30 member constructed to engage in a chimney thimble and having adjustable clamping means, a fixed stop mounted on the base, a plate movably mounted on the base and carrying a stove pipe locking boss, and a wedge shaped lever swinging between the plate and the base for displacing the former. 35
2. In a device for fastening stove pipes in chimney thimbles, a base having a clamping lug, a shank extending from the base 40 and having an offset slotted portion, a stud carried by the shank, an extension hook slideable through the slotted portion of the shank and having openings receiving the stud, a clamping member mounted on the base, a 45 stop on the clamping member, an upstanding boss on the clamping member, and a wedge shaped lever pivoted between the base and the said member.

In testimony whereof I affix my signature. 50

ANTHONY SCHUCH.
